SHARPENING DEVICE.

1,240,540.

Specification of Letters Patent.

Patented Sept. 18, 1917.

Application filed June 18, 1914. Serial No. 845,810.

To all whom it may concern:

Be it known that I, RENÉ CANDELIEZ, citizen of the French Republic, residing at Uccle 307, Rue Vanderkindere, Belgium, 5 have invented a new and useful Improvement in Sharpening Devices; and I do hereby declare the following to be a full, clear, and exact description of the same.

This invention is based on the following 10 theoretical considerations, reference being had to razors, as an example.

Figures 1 and 2 are diagrammatic cross-sectional views which taken with the description explain the theory of the application's device;

Fig. 3 is a plan of the sharpening device, part being removed.

Fig. 4 is a fragmental longitudinal section, taken on the line $d-d$ of Fig. 3; and

Fig. 5 shows a view partly in cross-section on the line $e-e$ of Fig. 3.

When, as is generally the case, a razor is being sharpened, the original cross-section of which is $C D E$ (Fig. 1), on a strop attached to an eye-bolt, or on a leather $A B$ stretched flat on a bar, it will be readily understood that the cutting edge C is worn out and disappears, the more quickly, the greater the thickness of the blade relatively 25 to its width, and that it has the tendency to assume the defective shape $c D E$ (the portion shown cross-hatched) or in other words, that the friction quickly blunts the edge and that the latter can be no longer formed 30 again, except on a thicker portion c of the blade, which is one of the most unfavorable conditions to the sharpening and to the life of the razor.

In order to obviate this too quick wearing 40 out, it will be logical to have for the friction plane $A B$ substituted a portion $a C E$ b (Fig. 2) of a circle with center O , tangent at C to the curvature $C E$ of the razor blade, so that the median line $C H$ of the symmetrical curvatures $C D$, $C E$ of the said 45 blade, which is also their common tangent, coincides at C with the tangent to the circle whose center is O and that thus the sharpening is only made tangentially to the 50 cutting edge without blunting it, as is the case with flat leather.

Among all the circles tangent to the cutting edge C , the most suitable one is obviously the circle having the same radius 55 of curvature, as the blade at the said point C , that is to say, the circle tangent to the

blade at its edge. If however it is taken into consideration that the curves $C D$, $C E$ of razors, are generally those of parabola, the formula giving the radius of the said tangent circle (I will not go into the calculation giving it) will be approximately the square of L divided by i , where L is the width of the blade and i its maximum thickness, and it will be seen that the radius in question is then always comparatively small. A sharpening apparatus based on this principle alone, cannot therefore be utilized, as the hand which guides the blade on an arc of very small radius, in practice would have 60 65 very great difficulty in maintaining, during the friction of the blade, simultaneous contact at the back and the edge of the razor.

The real solution of the problem consists in considering as elastic the portion $C E$ of the arc of circle arranged under the blade. By examining Fig. 2, it will be seen in fact that the central tangent $C H$ is at a distance $E H$ from the straight line $G E$ parallel to it and passing through E , equal to $\frac{i}{2}$. If 70 75 therefore we slide the back of the razor along $G E$, keeping $C H$ parallel to the said straight line $G E$, it will be sufficient if at each new position of the blade, we should always meet a point C of the sharpening device situated at the distance of $\frac{i}{2}$ from $G E$, 80 85 in order that the sharpening should take place tangentially to the cutting edge, which 90 is the desired result.

This condition is fulfilled in the device, forming the object of the present invention and which is illustrated, by way of example, in the annexed drawings.

The device is shown in plan in Fig. 3. The leather K covering, between its edges I , I , L , L , is assumed to have been removed for half its length. It will be seen that the handle Q is made removable, and can be secured by screwing, or in any other way, at either end of the instrument.

Fig. 5 is a cross-section on line $e-e$ (of Fig. 3) which is the most suitable for the explanation and which shows at M the hard wood bar forming the frame of the instrument. This bar is provided at each side with an extension J at a right angle to its plane and forming a supporting ledge. Between the said supporting ledges J J of 100 105 equal height, is placed an elastic part constituted by a leather envelop or case K K 110

covering a system of several rubber tubes F F embedded in a base P, also of rubber. The leather case thus provided with tubes, is lined inside with paper or fabric impermeable to grease in order to protect the rubber of the tubes. Its face in contact with the base P adheres by gluing to the inner bottom N N of the bar. The distance from the upper plane of the ledges to the upper plane of the leather of the case is substantially equal to half the thickness of the back of the razor.

In these conditions, if the said back is caused to slide by strongly and evenly pressing it on both ledges at the same time, and if the edge of the razor is held on the leather K previously coated with razor paste, without pressing or pressing very slightly on the edge, the working of the elastic part will comply exactly with the indications of Fig. 2, that is to say, the cylindrical surface which is constantly formed again under the blade, between the back sliding on the ledges and the cutting edge, remaining tangent to the leather, will produce in any position of the said blade, the circle tangent to the cutting edge. The sharpening is therefore effected tangentially to the latter, and no longer obliquely.

It must be pointed out here that the elastic part must be able to undergo a comparatively considerable deformation. It would not be sufficient in fact to place for instance the leather on an ordinary cotton fabric of 1-2 mm. thickness. It is necessary that the difference in level of the surface of the leather should be able to reach if required a value practically equal to half the thickness of the back of the razor, that is to say, in practice from $1\frac{1}{2}$ - $3\frac{1}{2}$ mm. Although different means such as folded fabrics or special cotton, wool, horse-hair, etc., fabrics, steel or other springs, metal fabrics, wires, rubber points, etc., could be used for attaining the object of the invention without departing from the principle thereof, nevertheless the idea of constituting the elastic part by a system of rubber tubes parallel to the bars, in the principal feature of the invention however the said tubes be placed, whatever be their number, even one, which could be an air tube similar to the inner tube of bicycles.

Also, the form illustrated seems to be the best adapted for the handle Q of the instrument. The said handle is made removable and can be fixed to either extremity of the bar so that, when changing its place from time to time, the elastic portion and the leather of the instrument will work and wear out both symmetrically and uniformly. Any other suitable means could also be used for the same purpose.

The present invention can be applied without any changes being made, to any kind of

sharp blades, particularly to razor blades of any system: ordinary razors with fixed or interchangeable blades or safety razors. In the latter case, it will be sufficient, in fact, to have the removable blades, for their sharpening, fixed to a handle similar to that of an ordinary razor, for the purpose of obtaining a tangential sharpening by means of the instrument described.

It goes without saying that the instrument can be double-faced, symmetrically with respect to the straight line T V dividing the thickness of the bar into equal parts. It goes also without saying that the theoretical distance from the top of the ledges to the top of the leather can be slightly or more or less modified, without departing from the invention. If required, the said ledges could even be dispensed with, the back of the razor being in this case supported by the flattened tubes. Furthermore, the envelop can be made of twisted fabric or of any material other than leather, and its surface, in contact with the bar, can be dispensed with, the elastic portion resting in this case directly on the said bar.

Having fully described my invention, what I claim and desire to secure by Letters Patent is:—

1. In a domestic sharpening device the combination of a bar; a leather envelop; and a plurality of parallel longitudinal tubes of uniform diameter, arranged side-by-side under said envelop, said tubes permitting the envelop to be deformed and to adopt the form of the blade and cutting edge from end-to-end thereof.

2. In a domestic sharpening device the combination of a bar; a leather envelop; and an elastic tube, open to the air, in said envelop.

3. In a domestic sharpening device the combination of a bar; a leather envelop; and a plurality of parallel elastic tubes open to the outside air and of uniform diameter, arranged side-by-side under said envelop, said tubes permitting the envelop to be deformed and to adopt the form of the blade and cutting edge from end-to-end thereof.

4. A sharpening device, comprising in combination, a bar, two lateral, longitudinal ledges of uniform height and perpendicular to the bar, a leather envelop arranged between the said ledges and resting on the bar, rubber tubes arranged in the interior of the leather envelop, parallel to the long sides of the bar, a rubber base in which are embedded the said tubes, substantially as described.

5. A sharpening device, comprising in combination, a bar, two lateral, longitudinal ledges of uniform height and perpendicular to the bar, a leather envelop arranged between the said ledges and resting on the bar, rubber tubes arranged in the interior of the

leather envelop, parallel to the long sides of the bar and the inner diameter of which is equal to half the thickness of the thick portion of the blade to be sharpened, substantially as described.

6. A sharpening device, comprising in combination, a bar, two lateral, longitudinal ledges of uniform height and perpendicular to the bar, a leather envelop arranged between the said ledges and resting on the bar, the said leather envelop being rendered impermeable to grease so as to protect the rubber, rubber tubes arranged in the interior of the leather envelop, parallel to the long sides of the bar, substantially as described.

7. A sharpening device, comprising in combination, a bar, two lateral, longitudinal ledges of uniform height and perpendicular

to the bar, a leather envelop arranged between the said ledges and resting on the bar, rubber tubes arranged in the interior of the leather envelop, parallel to the long sides of the bar, and a handle constructed to be fixed to either end of the bar, substantially as described.

8. A sharpening device, comprising, in combination, a bar, a leather envelop, uniform rubber tubes parallel to each other and arranged longitudinally under said envelop, the said tubes allowing the leather envelop to be deformed and adopt the form of the cutting edge in all positions of the blade to be sharpened, substantially as described.

In testimony whereof, I have signed my name to this specification.

RENÉ CANDELIEZ.
